UNITED STATES PATENT OFFICE

CHARLES C. THOMPSON, OF GLENDALE, CALIFORNIA

MEANS FOR DETERMINING THE DIP OF STRATA

Application filed September 22, 1924. Serial No. 739,151.

My present invention comprises a method of and means for determining the dip of strata penetrated at a depth below the surface of the earth; and it is an especial object of this invention to provide a method suitable for use in the location of anticlinal pockets, or the like, from which a flow of oil may be expected.

It is an object of this invention to provide a dip-determining method and means suitable for use in conjunction with, for example, a rotary drilling organization including a core barrel; and a preferred embodiment of my invention may involve the use of a core barrel in which a core is intended to stand stationary and integral with the ground rock during the cutting of the same and up to the moment of its withdrawal, this core barrel being however adapted ultimately to separate and lift the core, and means being provided and precautions being taken to make sure that the original orientation relatively to a reference plane (such as, for example, a meridian plane,) may be subsequently ascertained.

Other objects of my invention will appear from the following description of an illustrative embodiment thereof, taken in connection with the appended claims and the accompanying drawings, in which

Fig. 1 is a sectional view showing in elevation, but with parts broken away, an organization suitable for use in the practice of my invention.

Fig. 2 is a sectional view illustrating a simple type of core barrel in the act of removing a sample core, parts of the barrel being broken away.

Fig. 3 is a bottom plan view, taken as indicated by the arrow 3 of Fig. 2.

Fig. 4 is a plan view of a collar such as may optionally be employed in ascertaining the orientation of a string of drill pipe provided with a coring bit.

Fig. 5 is a sectional elevation similar to the lower part of Fig. 2, but showing the teeth in a core cutting position.

Referring to the details of that specific embodiment of my invention chosen for purposes of illustration, 11 may be a usual

string of pipe such as is used in rotary drilling, the joints or sections of this pipe being shown as connected by couplings 12 and the lower end thereof being provided with a "sub" 13, securing the same to a bit 14, shown as provided with a conveniently separable coupling section 15 and as provided at its lower end 16 with a substantially circular row of cutting teeth. The coring bit 14 or its equivalent may be rotated through the string 11 by any usual or preferred means such as a rotary table 17 provided with slips 18, the entire string being supported in a usual manner, as in part by a swivel head 19, or its equivalent.

Although I may employ any preferred type of coring bit, I have shown in Fig. 2 a bit consisting essentially of a steel tube or shell 14, shown as cut square across at its upper end and in internal threaded engagement with the separable section 15, the latter being shown as provided with a "pin" or nipple 20, for engagement by a usual box in the sub 13. The teeth at the lower end of the tube 14 are preferably cut and set as best indicated in Fig. 5, alternate teeth 16^a being bent outwardly in a manner favorable to suitable clearances on the outside of the shell 14, and inwardly projecting teeth 16^b being substantially vertical, but provided with a slight inward set, permitting a clearance between the inner surface of the shell and the outer surface of a core. It will be understood from Fig. 2 that the teeth 16^b are also adapted to be bent to a core engaging and breaking position by the application of a suitable downward pressure upon the coring bit and the inside of the shell 14. Suitable clearances on the inside are of especial importance, in order to make sure that frictional contact with the upwardly projecting core 21 shall not prematurely break the same from the ground rock, or occasion a disturbance of the strata or constituent materials thereof.

When the downward advance of the string shall indicate the cutting of a core of suitable length, the core may be separated or broken from the ground, as by discontinuing rotation of the drill and then causing the

same to sustain the entire weight of the string, the inwardly projecting teeth 16^b then acting as chisels, with a lifting or severing effect, as illustrated in Fig. 2.

5 In order to ascertain the dip of any strata comprised in the core 21, I may employ any suitable means for indicating, in a manner permitting exact observation, the orientation of the string 11 and the shell 14, serving as a core barrel, relatively to a plane of reference. For example, I may provide the uppermost section 11^a of drill tubing with a mark 22, this mark 22 being immediately above or having a known relationship to a mark 23, placed externally on the core barrel,—the latter mark being optionally carried across the line separating the head section 15 therefrom, and all couplings being optionally marked in a similar manner; and 10 I may provide on or opposite the upper section 11^a any suitable means for determining the orientation thereof after the string has been relieved of torsional strain and before lifting operations are commenced. For example, assuming the mark 22 to be directly above the mark 23, I may place upon the section 11^a a collar 24, such as is shown in Fig. 4, this collar being shown as graduated in degrees and as rotatable upon the section 11^a in such manner that its zero may be brought opposite any suitable point of reference, such as a fixed mark 25 indicating true or magnetic north. If, after the collar is so adjusted as to bring its zero to the north, a 15 note is made as to the relative position of the mark 22, carried by the section 11^a, it will be obvious that, even though no pains may have thereafter been taken to preserve the orientation of the string during the separation of the sections or "stands" thereof, the shell 14 may be ultimately restored to its true or original orientation, as by positioning the removable collar 24 concentrically thereon, with the mark 23 exactly opposite the position 20 in which the mark 22 was previously noted, and then again bringing the zero of the collar to the exact north. The core may be removed by simply holding it down on a horizontal surface or otherwise preserving its orientation while the shell 14 is separated therefrom. The core may thereafter be 25 studied in a restored orientation, reproducing its original or natural position in the earth, the dip of any strata therein being ascertainable by direct observation and measurement. As a matter of convenience, true or magnetic north may optionally be marked directly on the core, as by a vertical line N, in order to facilitate a study thereof at a remote point, such as a shop or laboratory, both the direction and angle of dip 30 being noted.

It will be obvious that a string 11 may be initially provided, during the assembly thereof and as each joint is completely

tightened, with a series of marks in the same vertical line; but I consider it advantageous to use a plumb-line or to make renewed or confirmatory observations in carrying a line or series of marks relatively downwardly on a string of pipe during the disassembly of the same into sections or stands; and this marking during withdrawal and disassembly may be a sufficient measure, available even when the coring drill has not initially been marked. 70

I require no complicated means for the practice of my invention, it being possible to rely upon a mark 25 scratched on a derrick floor or upon an arm 28 and used in conjunction with, for example, a crude protractor, to indicate the final position (relatively to the plane of reference indicated by the mark 22, or its equivalent) of an additional mark 26, which may be placed upon the section 11^a opposite the mark 25, after the string has come to rest; but I have shown the rotatable and removable collar 24 as provided with a compass 27, the employment of which may obviate the necessity for the use of means such as the arm 28 to carry the mark 25; and I have shown this compass as provided with degree marks, in order that, if desired, the collar may be left in a fixed position upon the section 11^a, or 85 its equivalent, and with its zero point opposite the mark 22, readings being then taken from the figures on the compass, shown as graduated in an opposite direction. 90

Although I have herein described one complete embodiment of my invention, it will be understood that various features thereof might be independently employed and also that various modifications might be made, by those skilled in the art, without the slightest departure from the spirit and scope of my invention as the same is indicated above and in the following claims. In these claims, I employ the term dip as referring to both the amount and the direction of inclination in relation to a horizontal plane or to another plane or planes of reference. 105

I claim as my invention:

1. An organization for ascertaining the direction of dip of unexposed strata, comprising: an operating string provided at its lower end with a core barrel for cutting a core without disturbing the original orientation thereof; and oriented means having a point of reference thereon, said oriented means being separate from said drill string, and said drill string having a series of marks thereon in predetermined azimuthal relation for cooperating with said point of reference to determine the original orientation of said core. 115

2. An organization for ascertaining the direction of dip of unexposed strata, comprising: an operating string provided at its lower end with a core barrel for cutting a 120

core without disturbing the original orientation thereof; and oriented means having a point of reference thereon, said oriented means being in a fixed position and separate from said drill string, and said drill string having a series of marks thereon in predetermined azimuthal relation for cooperating with said point of reference to determine the original orientation of said core.

10 3. An organization for ascertaining the direction of dip of unexposed strata, comprising: an operating string provided at its lower end with a core barrel for cutting a core without disturbing the original orientation thereof; and a fixed oriented pointer, suitably mounted above the ground surface relative to said drill string, said drill string having a series of marks thereon in predetermined azimuthal relation for cooperating 15 with said point of reference to determine the original orientation of said core.

20

In testimony whereof, I have hereunto set my hand at Carpinteria, California, this 13th day of September, 1924.

25 CHARLES C. THOMPSON.
